UNITED STATES PATENT OFFICE.

JAMES STONE, OF AURORA, ILLINOIS.

DESIGN FOR A CORSET.

SPECIFICATION forming part of Design No. 25,931, dated August 11, 1896.

Application filed August 30, 1895. Serial No. 561,038. Term of patent 14 years.

To all whom it may concern:

Be it known that I, JAMES STONE, a citizen of the United States, residing in the city of Aurora, county of Kane, and State of Illinois, have invented and produced a new and useful Design for Ornamentation of Corsets, of which the following is a specification, reference being had to the accompanying drawing, forming a part hereof.

10 The leading feature of my design is embodied in a corset having disposed or displayed theron, in the region of the waist, a girdle composed of a plurality of bands or strips, said bands or strips being parallel and substantially equidistant from each other at the rear part of the girdle and divergent at the front part thereof to broaden said girdle or make it of fan shape at that point.

15 The corset herein shown as embodying my design is provided, on its outer surface, with a plurality of bands or strips disposed horizontally upon the outer surface of the corset, in the region of the waist-line, and diverging at point constituting in appearance a 20 girdle broader at the point than at rear part of the corset. The individual bands or strips constituting the girdle as a whole are arranged parallel to each other and at substantially equal distances apart, at the rear 25 part of the corset, said bands or strips being, at the rear part of the corset, arranged to diverge, or in fan shape, so that the girdle, composed of said bands or strips, is broadened at

the front part of the corset. The divergent or broadened part of the girdle is shown as 35 composed of diverging groups of bands or strips, the bands of each group being arranged parallel and equidistant from each other, but the groups being arranged to diverge, as shown.

40 The bands or strips composing the girdle are preferably raised above the surface of the corset-body, and may be crossed and partly concealed by vertical bands or strips extending from top to bottom of the corset. In such 45 case the girdle is visible only between the vertical bands and presents a broken line or lines, but without destroying the effect or appearance of a girdle as a whole.

I prefer to render the girdle as a whole 50 more prominent or noticeable to the eye by the employment therein of material differing in shade, tint, texture, or color from the body of the corset.

I claim—

55 The design for a corset, substantially as shown and described.

In testimony that I claim the foregoing as my design I affix hereto my signature, in the presence of two subscribing witnesses, at 60 Chicago, Illinois, this 28th day of August, A. D. 1895.

JAMES STONE.
